US00D646967S

(12) **United States Design Patent**
Tamshe et al.

(10) **Patent No.:** **US D646,967 S**
(45) **Date of Patent:** **** Oct. 18, 2011**

(54) **CONTAINER**

(75) Inventors: **Amir Tamshe**, San Dimas, CA (US);
Victor Katseli, Hertzelia, IL (US);
Gandhi B. Sifuentes, Whittier, CA (US)

(73) Assignees: **Direct Pack, Inc.**, Sun Valley, CA (US);
Amir Tamshe, San Dimas, CA (US);
Victor Katseli, Hertzelia (IL)

(**) Term: **14 Years**

(21) Appl. No.: **29/380,575**

(22) Filed: **Dec. 8, 2010**

(51) LOC (9) Cl. **09-03**

(52) U.S. Cl. **D9/428; D9/425**

(58) **Field of Classification Search** D9/414,
D9/419, 424, 425–432, 500–504, 715–762;
D7/538, 549, 550.1, 601–603, 605, 629;
220/23.4, 23.6, 266, 281, 315, 318, 500,
220/659, 669, 674, 675, 696, 752, 760, 790,
220/793, DIG. 12, FOR. 117; 229/105, 117.09,
229/117.26, 189, 406, 407, 902, 905, 915.1;
206/499, 508, 557; D3/276

(57) **CLAIM**

The ornamental design for a container, as shown and described.

DESCRIPTION

FIG. 1 is a top perspective view of a container, showing our new design;

FIG. 2 is a left elevation view thereof;

FIG. 3 is a right elevation view thereof;

FIG. 4 is a front elevation view thereof;

FIG. 5 is a back elevation view thereof;

FIG. 6 is a top plan view thereof; and,

FIG. 7 is a bottom plan view thereof.

The channel shown in broken lines is unclaimed environment, and forms no part of the claimed design.

1 Claim, 5 Drawing Sheets
